Application June 6, 1933, Serial No. 674,578

13 Claims. (Cl. 101—345)

This invention relates to means which is designed and adapted for obtaining a uniform distribution of ink on a flat printing form of a printing press in the operation of the press.

The invention may be used advantageously in conjunction with a flat bed two-revolution press having inking means including distributor rollers for inking the printing form in response to the reciprocation of the latter, said rollers being mounted so as to be moved into positions to take them out of ink-distributing action to hold a quantity of ink in reserve or abeyance, and means to move said rollers for the aforesaid purpose, and also to allow said rollers to move into positions for ink-distributing action, so that the ink held in reserve or abeyance will be distributed uniformly to the advanced or leading portion of the form to give a substantially equal distribution of the ink throughout the entire area of the form.

Some of the advantages of the invention are as follows: it saves ink; it does away with roller streaks, due to uneven ink distribution; it eliminates offset and smut to a maximum; it does not interfere with speed or production; it produces a better grade of work; it produces an even color on the printed sheet; and it can be applied to all flat bed presses.

The nature of the invention and its distinguishing features and advantages will appear from the following specification when read in connection with the accompanying drawings, in which

Figure 1 is a fragmentary perspective view in dot-and-dash lines, of a two-color flat bed two-revolution press selected to illustrate the invention, which is shown applied thereto, the novel features being shown in full lines;

Fig. 2 is an enlarged fragmentary side view and part section illustrating certain features of the invention;

Fig. 3 is a diagrammatic view illustrating the inking means and bed embodying the ink plate and printing form, said bed being shown in its forward position to receive ink from the usual duct or roller;

Fig. 4 is a view similar to Fig. 3, but showing the bed in its advanced position in which ink is transferred from the ink plate to the form rollers of the ink-distributing means;

Fig. 5 is a view similar to Fig. 3, but showing the bed in return movement and the printing form being inked, during which the distributor rollers are taken out of ink-distributing action to hold a quantity of ink in reserve or abeyance;

Fig. 6 is a view similar to Fig. 3, but showing the bed advancing and the distributor rollers having the reserve ink down in distributing positions to distribute ink to the leading or advanced

area of the printing form to obtain a full and uniform or equal distribution of the ink on the entire area of the form.

Referring now more particularly to the drawings, it will be apparent that the invention is shown applied to a flat bed two-revolution type of press, a portion of which is shown in dot-and-dash lines, by way of example. This type of press includes a reciprocating bed 10, which carries the usual ink plate 11 and printing form 12. It is to be understood that ink is transferred to the plate 11 from a fountain 13, by the swinging duct or roller 14 as the bed 10 reaches its forward position. The ink which is transferred to the plate 11 is distributed thereon by an assembly of rollers consisting of angle rollers 15, which roll in contact with the plate 11, and vibrator rollers 16, which cooperate with the rollers 15 to obtain the proper distribution of the ink on the upper surface of the plate 11. Inking means is also employed for inking the printing form 12, and consists of an assembly of rollers, consisting of form rollers 17, vibrator rollers 18, and distributor rollers 19. The rollers 17 are positioned to receive ink from the plate 11, and to roll in contact with the printing surface of the form 12 to ink the latter. The vibrator rollers 18 and distributor rollers 19 cooperate with the form rollers 17 to obtain the desired distribution of the ink.

In accordance with the invention the distributor rollers 19 are mounted for movement into and out of ink-distributing positions with respect to the other rollers 17 and 18. To this end the trunnions or journals 20 on the opposite ends of the rollers 19 are received, respectively, in socket bearings 21 on the framework of the press. It will therefore be understood that the distributor rollers 19 may be moved up and down. The rollers 19 are moved up into positions to take them out of ink-distributing action, for the purpose of holding a quantity of ink in reserve or abeyance, and the said rollers 19 are allowed to move downward into positions for ink-distributing action, so that the ink held in reserve or abeyance will be distributed through the intervention of the rollers 18 and 17, to the printing form 12 in response to the movement of the bed 10. In order to accomplish this result there is provided a rod 22 having up and down sliding movement in guides 23 secured to the framework of the press. An arm 24, which is horizontally disposed in its active position, has one end thereof pivotally connected with the upper end of the rod 22, as at 25. The arm 24 may be swung upwardly on its pivot from the horizontal position into an inactive position in order not to present an obstruction when removing the rollers 17 and 18. A shoulder 26 on the arm 24 engageable with the rod prevents its movement downwardly.

beyond a horizontal position. The arm 24 is disposed so as to engage the trunnions or journals 20 of two of the distributor rollers 19, as shown most clearly in Fig. 2. The lower end of the rod 22 has connected therewith a roller 27, which is acted on by a cam 28 on the rotary cam shaft 29 of the press. The cam 28 acting on the roller 27, causes the rod 22 and its arm 24 to move up and down in response to the rotation of the shaft 29, and this is performed in timed accord with the reciprocation or motion of the bed 10 for the purpose of elevating the distributor rollers 19 and to let them move downwardly for the aforesaid purpose. It will therefore be understood that means is provided for moving the distributor rollers 19 into positions to take them out of ink-distributing action in order to hold a quantity of ink in reserve or abeyance and to let them come down into positions for ink-distributing action to feed the ink in reserve or abeyance at the proper time so that it will be distributed substantially over the leading half of the form 12. This means is arranged in the present instance only on one side of the press, and it therefore will be apparent that the distributor rollers 19 will be canted to accomplish the desired result. If desired, similar means may be arranged on both sides of the press to cooperate with the rollers 19 for the intended purpose.

It will be obvious that if the distributor rollers 19 were not held up with a reserve supply of ink, the form rollers 17 would be nearly depleted of their supply of ink and while ink would be spread on the form 12 it would not be spread uniformly or equally throughout the entire area of the form 12, whereas when the distributor rollers 19 come down with the reserve supply of ink they will make up for the deficiency mentioned at the proper time and furnish ink over the entire area of the form 12 by distributing the reserve supply of ink on substantially the leading half of the form 12.

From the foregoing it will be obvious that after the bed 10 has been moved forwardly and rearwardly a number of times without printing, ink will be transferred to the plate 11 from the fountain 13 by the roller 14. This ink is spread uniformly on the plate 11 by the assembly of rollers 15 and 16. As the bed 10 moves forwardly toward the cylinder indicated at C, ink from the plate 11 will be transferred to the assembly of rollers 17, 18 and 19, as shown in Fig. 4. Upon rearward or return movement of the bed 10, ink will be distributed to the form 12 by the rollers 17. During this return movement of the bed 10 and approximately at the time one-half of the form 12 has been inked, the distributor rollers 19 are elevated or canted to take them out of ink-distributing action to hold the ink thereof in reserve. Meanwhile the rollers 17 are distributing ink to the leading half of the form 12. When the bed 10 is again moved forwardly toward the cylinder C, the distributor rollers 19 are allowed to move downwardly by the actuating means into positions for ink-distributing action, as the leading edge of the form approaches the rollers 17. The reserve supply of ink on the rollers 19 will be transferred to the leading half of the form 12 through the intervention of the rollers 18 and 17. In this manner, the form 12 will be inked uniformly throughout the entire area thereof and because of this manner of feeding or distributing the ink to the form 12 the advantages hereinabove mentioned may be achieved.

1. In a printing press having a reciprocatory

printing form, inking means including distributor rollers for inking said form in response to the reciprocation of the latter, said rollers being mounted so as to be moved into positions to take them out of ink-distributing action to hold a quantity of ink in reserve, and means to move said rollers for the aforesaid purpose, said last means being operable to allow said rollers to move into positions for ink distributing action during the early part of the forward movement of the printing form, so that said inking means will distribute the reserve ink to the advanced portion of said form in each forward movement of the latter.

2. In a printing press having a reciprocatory printing form, inking means including distributor rollers for inking said form in response to the reciprocation of the latter, said rollers being canted so as to be moved into positions to take them out of ink-distributing action to hold a quantity of ink in reserve, and means to cant said rollers for the aforesaid purpose, said last means being operable to allow said rollers to move into positions for ink-distributing action during the early part of the forward movement of the printing form, so that said inking means will distribute the reserve ink to the advanced portion of said form in each forward movement of the latter.

3. In a printing press, in combination, a reciprocating printing form, form inking means including an ink distributor roller mounted for movement into and out of ink distributing position; and means to cause the movement of said roller out of ink distributing position, and to hold it out during a late part of the rearward travel of the printing form, to hold ink in reserve, said means being operable to allow said roller to move into ink distributing position, and to remain in said last position during the early part of the forward travel of the printing form, to distribute ink more uniformly throughout the printing form by distributing the reserve ink from the roller.

4. In a printing press, in combination, a reciprocating printing form, an assembly of inking rollers consisting of rollers which transfer ink directly to said printing form, and ink distributing rollers, said distributing rollers being mounted so as to be moved into positions to take them out of ink distributing action to hold a quantity of ink in reserve, and means to move said distributor rollers for the aforesaid purpose, said last means being operable to allow said distributor rollers to move into positions for ink distributing action, so that said assemblage will distribute the reserve ink to a definite part of the printing surface of said form each time the latter moves forwardly.

5. In a printing press, in combination, a movable printing form, form inking means including ink distributor rollers mounted for movement into and out of ink-distributing positions; and means to cause the movement of said rollers into and out of said positions in timed accord with the movement of the printing form, so that said rollers will be in ink-distributing positions during the early part of the forward movement of the printing form, and so that said rollers will be out of ink-distributing positions during the late part of the rearward movement of the printing form, for the purpose of distributing ink more uniformly throughout the printing form by distributing a reserve supply from said rollers to the remainder of said means and then to substantially the forward half portion of the form in each forward movement of the latter.

6. In a printing press, in combination, a movable printing form, form inking means including ink distributor rollers mounted for movement into and out of ink-distributing positions; a movable member engageable with the rollers, and means to cause the movement of said member to cause the movement of said rollers into and out of said positions in timed accord with the movement of the printing form, so that said rollers will be in ink-distributing positions during the early part of the forward movement of the printing form, and so that said rollers will be out of ink-distributing positions during the late part of the rearward movement of the printing form, for the purpose of distributing ink more uniformly throughout the printing form by distributing a reserve supply from said rollers to the remainder of said means and then to substantially the forward half portion of the form in each forward movement of the latter.

7. In a printing press, in combination, a movable printing form, form inking means including ink distributor rollers mounted for movement into and out of ink-distributing positions; a reciprocal member engageable with the rollers, and means to cause the reciprocation of said member to cause the movement of said rollers into and out of said positions in timed accord with the movement of the printing form, so that said rollers will be in ink-distributing positions during the early part of the forward movement of the printing form, and so that said rollers will be out of ink-distributing positions during the late part of the rearward movement of the printing form, for the purpose of distributing ink more uniformly throughout the printing form by distributing a reserve supply from said rollers to the remainder of said means and then to substantially the forward half portion of the form in each forward movement of the latter.

8. In a printing press, in combination, a reciprocal printing form, form inking means including ink distributor rollers mounted for movement into and out of ink-distributing positions; mechanism which reciprocates the printing form, and means operated in timed accord with said mechanism to cause the movement of said rollers into and out of said positions, so that said rollers will be in ink-distributing positions during the early part of the forward movement of the printing form, and so that said rollers will be out of ink-distributing positions during the late part of the rearward movement of the printing form, for the purpose of distributing ink more uniformly throughout the printing form by distributing a reserve supply from said distributor rollers to the remainder of said means and then to substantially the forward half portion of the form in each forward movement of the latter.

9. In a printing press, in combination, a reciprocating printing form, inking means including inking rollers, vibrating rollers which constantly cooperate with said form rollers, and distributor rollers which cooperate with said vibrating rollers, said distributor rollers being mounted for movement into and out of contact with said vibrating rollers; and means to cause the movement of said distributor rollers into and out of contact with said vibrating rollers in timed accord with the reciprocation of the printing form, for the purpose of distributing ink more uniformly throughout the printing form by distributing a reserve supply from said distributor rollers to

the remainder of said means to a portion of the form in each forward movement of the latter.

10. In a printing press, in combination, a movable printing form, form inking means including ink distributor rollers mounted for movement into and out of ink-distributing positions; and means to cause the movement of said rollers into and out of said positions in timed accord with the movement of the printing form, so that said rollers will be in ink-distributing positions during the early part of the forward movement of the printing form, and so that said rollers will be out of ink-distributing positions during the late part of the rearward movement of the printing form, for the purpose of distributing ink more uniformly throughout the printing form by distributing a reserve supply from said rollers to the remainder of said means and then to substantially the forward half portion of the form in each forward movement of the latter, said means including a member engageable with said rollers and having up and down movement, and a rotary cam which operates said member.

11. In a printing press, in combination, a movable printing form, form inking means including ink distributor rollers mounted for movement into and out of ink-distributing positions; a movable member engageable with the rollers, and means to cause the movement of said member, as the printing form is moving rearwardly, to cause the movement of said rollers out of ink-distributing positions, and to retain said rollers in the out positions during the late part of the rearward movement of the printing form, said last means allowing said member to move in an opposite direction, as the printing form is moving forwardly, to allow the movement of said rollers into ink distributing positions, during the early part of the forward movement of the printing form.

12. In a printing press, in combination, a movable printing form, form inking means including ink distributor rollers mounted for movement into and out of ink-distributing positions, a movable member engageable with the rollers, a rotary shaft, and a cam on said shaft to cause the movement of said member, as the printing form is moving rearwardly, to cause the movement of said rollers out of ink-distributing positions, and to retain said rollers in the out positions during the late part of the rearward movement of the printing form, said cam allowing said member to move in an opposite direction, as the printing form is moving forwardly, to allow the movement of said rollers into ink-distributing positions, during the early part of the forward movement of the printing form.

13. In a printing press, in combination, ink-distributor rollers mounted for movement into and out of ink-distributing positions, a slideable rod having up and down movement, an arm articulated with said rod so as to be freely engageable with said rollers into an active position to move them, and also movable to an inactive position, and means to cause the up movement of the rod, to cause said arm while in its active position to move said rollers out of ink-distributing positions, and allowing the down movement of the rod and arm so that the rollers may move into their ink-distributing positions.
